UNITED STATES PATENT OFFICE.

EDITH A. MORGAN, OF CHESTER, ENGLAND.

CORSET SUSPENDERS.

Application filed January 17, 1923. Serial No. 613,265.

To all whom it may concern:

Be it known that I, EDITH AMY MORGAN, a subject of the King of Great Britain, residing at Chester, in the county of Chester and Kingdom of England, have invented certain new and useful Improvements in Corset Suspenders, of which the following is a specification.

This invention relates to improvements in suspenders adapted to be worn with corsets such suspenders being of the type comprising a garter or band fastened around the wearer's limb below the knee and connected by adjustable suspending straps to the lower edges of the corset. The particular purpose of the device is to keep the corset well down at the back and sides and prevent it from working up during wear and to also prevent the circulation in the wearer's limb being impeded by a tight-fitting garter.

A special feature of my suspender is the absence therein of tight-fitting garters which are a constant source of discomfort. The invention is based on a different principle from these devices and consists of providing a comparatively loose knee-band which, in use, is pulled up at the back away from the wearer's limb, thus tensioning the knee-band against the limb below the bulge of the knee-cap which prevents the band working up above the knee. The knee-band acts not only to keep the stocking up, but keeps the corset well down and prevents it from working up during wear. More specifically, this result is obtained by providing a comparatively loose knee-band to the rear portion of which a suspending strap or straps are connected while the upper ends of the strap or straps are attached to the lower edges of the corset at the back and sides. This results when the device is in use, in the loose-fitting knee-band being pulled up at the back by the suspending strap or straps and this causes the band to be tightened under the bulge of the knee-cap which prevents the band working up above the knee.

The invention will be further described with reference to the accompanying drawings, in which:—

Figure 1 is a perspective view of my improved corset suspender.

Figure 2 shows the suspender in use.

Figure 3 detail of a modification.

My suspender comprises two or three

straps A of elastic or non-elastic webbing or other suitable material which when the device is in use, are situated at the back and side of the leg, as shown in Fig. 2. These straps are attached to the lower edge of the rear half of the corset B or other body encircling garment, or to tabs thereon, in any suitable way, for instance, by means of stitching as at C, or by any suitable clip or fastening device such as D. At their lower end these straps are looped as at E and connected to an adjustable clip or buckle F of any known kind for enabling the length of the strap to be regulated to suit the wearer.

The band G which encircles the leg just below the knee, can be made of elastic or non-elastic webbing, or other suitable material, for example, of fancy ribbon, and at its ends is fitted with a buckle H or a clasp fastener, of any suitable size and kind. It is an ordinary buckle or clip for regulating the length of the band to suit the requirements of the wearer. When the knee-band G is of non-elastic material, it is preferably lined with a lining M of a material that will give a better grip, such as velvet or suède. The band G, instead of being all of one material, might be fitted with leather end pieces or straps. The band G is fastened at the front just below the knee by means of the buckle or clasp.

The band G is preferably connected to the lower looped ends of the suspension straps A by means of a loop of round elastic or non-elastic cord, tape, or other suitable material J which is passed through the loops E on the straps A, and attached at its ends to the knee-band in any suitable and desired way, such as by stitching at K through the loops L.

The mode of use of my improved corset suspender is evident from Fig. 2.

In an alternate arrangement (shown in Fig. 3) at or about mid-length the knee band may be provided with two or three separate loops or divisions N, according to the number of suspension straps. These loops or divisions may be made from the material of the strap itself or be attached to the band G. For instance, the band may be made in two layers of material, the loop portions or divisions being formed by transverse stitching O. Through each of these knee-band loops or divisions the looped end E of suspension strap A is

passed. The front layer of the divided band may be threaded through one of the loops, and the back layer through another suspension strap loop alternately according to 5 number used. By using separate divisions or loops on the knee-band the suspension straps A are prevented from overlapping or over-riding each other at their lower end.

The band is fastened on to the leg with 10 sufficient looseness to prevent the circulation being impeded and the bend of the knee keeps the band in position. My attachment causes no drag on the stocking.

The device is very simple to adjust, and 15 an important advantage is that no readjustment in its length is necessary no matter what the length of the stocking may be and it has only the one fastening. It has the distinct advantage when in use of 20 keeping the corset well down.

The device may be made and sold as part and parcel of the corset, or may be sold separately and attached to any corset or any body encircling garment.

25 I declare that what I claim is:—

1. In combination, a body encircling garment; a loose-fitting knee-band; and suspending straps connected at their upper ends

to the rear half of the body garment and at their lower ends to only the rear portion of the knee-band, so as to cause the knee-band, when in use, to be pulled up at the back away from the wearer's limb and tighten the front of the knee-band against the limb below the knee-cap. 30 35

2. In combination, a body encircling garment; a loose-fitting knee-band having only its rear portion provided with a plurality of loops; and a plurality of suspending straps connected at their upper 40 ends to the back and sides of the body garment and provided at their lower ends with loops engaging with and freely movable in said knee-band loops, whereby to cause the knee-band, when in use, to be pulled up at the back away from the wearer's limb and tighten the front of the knee-band against the limb below the knee-cap. 45

In witness whereof, I have hereunto signed my name this 30th day of December 50 1922, in the presence of two subscribing witnesses.

EDITH A. MORGAN.
